(No Model.)

T. BRAUN.
SEEDING MACHINE.

No. 351,247.

Patented Oct. 19, 1886.

UNITED STATES PATENT OFFICE.

THEOBALD BRAUN, OF ATHY, ASSIGNOR OF ONE-HALF TO ADAM FEIK,
OF VOLCANO, WEST VIRGINIA.

SEEDING-MACHINE.

SPECIFICATION forming part of Letters Patent No. 351,247, dated October 19, 1886.

Application filed March 29, 1886. Serial No. 196,983. (No model.)

To all whom it may concern:

Be it known that I, THEOBALD BRAUN, a citizen of the United States, and a resident of Athy, in the county of Wood and State of West Virginia, have invented certain new and useful Improvements in Seeding-Machines; and I do hereby declare that the following is a full, clear, and exact description of the invention, which will enable others skilled in the art to 5 to which it appertains to make and use the same, reference being had to the accompanying drawings, which form a part of this specification, and in which—

Figure 1 is a side view of my improved seeding-machine. Fig. 1^x is a transverse section through the seed-box and the beam taken on line $\alpha\alpha$, Fig. 1, the sprocket-wheel and outer washer being shown in section. Fig. 2 is a similar view of the same seen from the other side. Fig. 3 is a front view of the machine. Fig. 4 is a longitudinal vertical sectional view of the machine; and Fig. 5 is a perspective detail view of the shaft of the seed-disk and its sprocket-wheel and disk, showing portions broken away.

Similar letters of reference indicate corresponding parts in all the figures.

My invention has relation to that class of seeding-machines in which a seed-box is secured upon a beam having handles and opening and covering plows similar to a cultivator-beam, and in which a wheel is journaled between arms projecting from the forward end of the beam, and has suitable gearing which 30 connects it to the seed disk or wheel in the seed-box, imparting motion to the said disk; and it consists in the improved construction and combination of parts of such a machine, as hereinafter more fully described and claimed.

40 In the accompanying drawings, the letter A indicates the beam, which is provided at its rear end with the handles B B, and which is formed with the standard C, to the lower end of which the opening-shovel D is secured, and 45 to the rear side of which the seed-tube is secured, as shown at E, and the forward end of the beam which is provided with a suitable clevis or hook for the attachment of the team is formed with two downwardly-projecting

braced arms, F F, having bearings G at their 50 lower ends. The shaft H of the drive-wheel I has its ends journaled in these bearings, and a sprocket-wheel, J, is secured upon the shaft at the side of the drive-wheel, revolving with the same. The rear portion of the beam is 55 provided with a longitudinal slot, K, to the rear of the standard, and bearings L L are formed in the sides of this slot, having removable upper portions, and a shaft, M, is journaled in these bearings and has the seed-disk 60 N secured removably upon it between the bearings. A ratchet-wheel, O, having its teeth facing forward, is secured upon one end of this shaft, and is engaged by a pawl, P, which is pivoted forward of the shaft, and may be tilted 65 out of engagement with the ratchet-wheel. The other end of the shaft outside the other bearing is provided with a disk or washer, Q, turning upon the shaft, and a sprocket-wheel, R, having a sprocket-chain, S, passing over 70 it and the wheel upon the drive-shaft, revolves upon the seed-shaft outside of the washer. Another washer, T, revolves upon the shaft outside of the sprocket-wheel, and this washer and the sprocket-wheel are formed with a 75 notch or groove, U and V, in their bores, which notches or grooves may register with a groove, W, in the end of the shaft. A key, X, is secured by means of a chain, Y, to the outer washer, which is retained upon the shaft by 80 means of a pin or key, Z, and may be inserted into the grooves, when they have all been brought to register, when the shaft will revolve with the sprocket-wheel, while, when the key is removed, the sprocket-wheel may revolve 85 upon the seed-shaft.

The forward part of the portion of the seed-disk, which projects below the slot in the beam, is covered and surrounded by the enlarged upper end, A', of the seed-tube, preventing any 90 grain from being lost.

The seed-box B' is secured upon the upper side of the beam over the slot in the same, having hasps C at its ends, which hasps fit over staples D' upon the top of the beam, and 95 are retained by means of hooked pins E', inserted through the staples, and the forward end of the seed-box is provided with a parti-

tion, F', which is immediately above the highest point of the seed-disk, and which is provided at its lower end with a flexible brush, G', for the purpose of smoothing the grain contained in the seed cup or cups H' in the periphery of the seed-disk.

The sides of the seed-box are scooped out toward the periphery of the seed-disk, as shown at I', for the purpose of carrying the seed toward the seed-disk, and a block, J', bears with its forward end against the rear portion of the periphery of the seed-disk, being secured in the bottom of the seed-box, and prevents any seed from dropping out at the rear end of the box, while the seed-disk carries the seed in its cup or cups forward through the empty forward half of the seed-box down into the wide upper end of the seed-tube.

It will be seen that when the machine is in operation the pawl is thrown out of engagement with the ratchet-wheel upon the seed-shaft allowing it to revolve, and the key inserted through the grooves in the bores of the washer and sprocket-wheel and in the shaft, causing the shaft and the seed-disk to be revolved by the sprocket-wheel; but when the machine is to be transported from one place to another the key is removed, when the sprocket-wheel may revolve upon the shaft, and the pawl is engaged with the ratchet-wheel, preventing the sprocket-wheel from carrying the shaft and disk with it in its revolutions.

The washer upon the outer end of the seed-shaft serves to give the key a better hold in the groove of the sprocket-wheel, and to brace the said key, confining a greater portion of the key than if the washer were removed.

A marker-arm, K', has its inner end, L', bent downward, and rigidly secured in a rectangular block, X', which fits removably in an obliquely-cut rectangular hole in the forward end of the beam, and a rod, M', is suspended from the outer end of the arm and braced by means of a rod, N', pivotally secured to the middle of the arm and of the rod. This rod depends from the outer end of the arm and will mark in the soil a line, which indicates

the next row to be planted, and the arm may be turned to mark on either side of the seeder 50 by reversing said block X'.

Two arms, O' O', are secured at their forward ends to the opening standard, and have the covering-shovels P' P' secured upon their downwardly-curved rear ends, and are connected 55 by a cross-piece, Q', and these shovels will cover the seed and form a ridge over it, which will have two low ditches or grooves at its sides, which will absorb the water and prevent the grain from being rotted by too much water. 60

The seed-disk has preferably only one cup in its periphery when it is used for planting corn or other seed which is planted in hills, but when it is desired to either plant in hills at a less distance between each other or to use 65 the machine as a drill a disk is used with a number of cups in the periphery, and the said disk may be placed upon the seed-shaft by removing the seed-box, raising the upper halves of the bearings for the shaft, and removing 70 either the ratchet-wheel or the washer, sprocket-wheel, and outer washer, when the disk upon the shaft may be removed and the other disk placed upon the shaft.

Having thus described my invention, I claim 75 and desire to secure by Letters Patent of the United States—

1. In a seeding-machine, the combination of a grooved shaft carrying the seed-disk, the washer Q, the sprocket-wheel R, the washer 80 T, the removable key X, the pin Z, the ratchet-wheel O, and the pawl P, substantially as and for the purpose set forth.

2. In a seeding-machine, the combination of the beam A, provided with an obliquely-cut 85 hole in the forward end, the rectangular block X', the rod K', rigidly secured in said block, the rod M', and the brace N', substantially as and for the purpose set forth.

In testimony that I claim the foregoing as 90 my own I have hereunto affixed my signature in presence of two witnesses.

THEOBALD BRAUN.

Witnesses:

ADAM FEIK,
R. ALEXANDER.
